Patented Aug. 28, 1917.

Inventor:
William L. Geddes,
Charles N. Butler
By Attorney.

UNITED STATES PATENT OFFICE.

WILLIAM L. GEDDES, OF MERION, PENNSYLVANIA.

GAGE.

1,238,127.

Specification of Letters Patent. Patented Aug. 28, 1917.

Application filed January 24, 1917. Serial No. 144,166.

To all whom it may concern:

Be it known that I, WILLIAM L. GEDDES, a citizen of the United States, residing at Merion, Montgomery county, Pennsylvania, 5 have invented certain Improvements in Gages, of which the following is a specification.

This invention is an improvement in gages of the type commonly used for showing the 10 water level in steam boilers and its primary object is to secure correct indication under varying conditions.

In gages for indicating the water level in steam boilers, particularly, the passages 15 which should be open are sometimes stopped, by the sticking of check valves or other obstruction, whereby the glass fails to show the correct level of the water.

In accordance with my invention, in its 20 preferred form, a plurality of passages are provided between each end of the glass and the steam and water drum of the boiler, a valved by-pass being provided for obtaining controlled flow around the usual valved 25 ports.

The characteristic features of my invention are embodied in the gage illustrated in the accompanying drawing, of which the following is a description.

30 The drawing is a part sectional elevation of the gage embodying my improvements.

As illustrated in the drawing, the gage fixtures 1 and 1' are connected together by the glass 2 and the tie rod 3, and to the 35 boiler drum 4 by the couplings 5 and 5'.

The drum 4 communicates by the coupling 5 with a passage 7 which extends through the fixture 1 to the bottom of the glass 2, the passage containing the port 8 adapted to be 40 closed automatically by the ball or check valve 9 and the port 10 adapted to be closed by the valve 11 having the manually operated stem 12. A branch passage 13 in the fixture 1 provides a by-pass from the coupling 5 around the ports 8 and 10, the branch passage being provided with an outlet port 14 adapted to be closed by the valve 15 having the manually operated stem 16. The fixture 1 is provided with the usual 45 blow-off cock 17.

The drum 4 communicates by the coupling 5' with the passage 7' extending through the fixture 1' to the top of the glass 2, the passage containing the port 8' controlled by 50 the automatic ball or check valve 9' and the

port 10' controlled by the valve 11' having the manually operated stem 12'. A branch passage 13' in the fixture 1' provides a by-pass from the coupling 5' around the ports 8' and 10', the branch passage being provided with an outlet port 14' controlled by the valve 15' provided with the manually operated stem 16'.

In operation, the valves 9, 11, 9' and 11' are normally open and the valves 15 and 15' 60 are closed, when the gage operates in the usual manner if in good order. But it sometimes happens that the passage 7 or 7' becomes obstructed, as by the sticking of the valve 9 or 9' in the ports 8 or 8' or by the 65 accumulation of obstructing matter, which prevents free circulation between the drum and the glass through the passages 7 and 7'. The condition of these passages can be tested and the correct water level in the boiler 70 determined by opening the valves 15 and 15', permitting flow through the by-passages 13 and 13'.

It will be understood that the gage can be blown out in various ways when the cock 75 17 is open, as by closing the valves 11' and 15' and opening the valves 15 and 11, when the lower fixture is washed out through the by-pass 13, and by closing the valves 11 and 15 and opening the valves 15' and 11', when 80 steam is blown through the gage by way of the upper by-pass 13'.

Having described my invention, I claim:

1. The combination with a boiler, of a 85 gage comprising a sight tube, a fixture containing a passage communicating with said tube, a passage communicating with said boiler and said passage first named, a manually operated valve controlling communication between said passages, an automatic 90 valve between said valve first named and said boiler, a by-pass communicating with said first and second named passages, and a valve controlling said by-pass.

2. A gage comprising a pair of fixtures 100 each containing a passage, a glass connecting the passages of said fixtures, an automatic check valve adapted for controlling each of said passages, a manually operated valve adapted for controlling each of said 105 passages, a by-pass around said valves in each of said fixtures, and a valve for controlling each of said by-passes.

3. The combination with a boiler drum, 110 of a gage comprising a pair of fixtures each

containing a passage connected with said drum, a glass tube connecting said passages, an automatic valve adapted for checking flow from said drum through each of said 5 passages to said glass, a manually operated valve adapted for stopping the flow from said drum through each of said passages to

said glass, and a by-pass in each fixture for connecting said drum with each end of said glass.

10

In testimony whereof I have hereunto set my name this 18th day of January, 1917.

WILLIAM L. GEDDES.
